UNITED STATES PATENT OFFICE

135,893

DESIGN FOR A CORRESPONDENCE FOLDER OR SIMILAR ARTICLE

Jack E. Schenker, Chicago, Ill.

Application April 2, 1943, Serial No. 109,893

Term of patent 7 years

To all whom it may concern:

Be it known that I, Jack E. Schenker, a citizen of the United States, residing at Chicago, in the county of Cook and State of Illinois, have invented a new, original, and ornamental Design for a Correspondence Folder or Similar Article, of which the following is a specification, reference being had to the accompanying drawing, forming a part thereof.

In the drawing:

Fig. 1 is a top edge view of a correspondence folder in folded position;

Fig. 2 is a face view thereof;

Fig. 3 is a top edge view thereof in partly opened position;

Fig. 4 is a face view thereof opened as illustrated in Fig. 3.

Fig. 5 is a top edge view in completely opened position; and

Fig. 6 is a face view thereof opened as illustrated in Fig. 5.

I claim:

The ornamental design for a correspondence folder or similar article, substantially as shown.

JACK E. SCHENKER.
